UNITED STATES PATENT OFFICE.

CLARENCE WAINRIGHT WOOD, OF NEW YORK, N. Y.

DESIGN FOR A WAGON-BODY.

SPECIFICATION forming part of Design No. 28,236, dated February 1, 1898.

Application filed June 28, 1897. Serial No. 642,753. Term of patent 7 years.

To all whom it may concern:

Be it known that I, CLARENCE WAINRIGHT WOOD, a citizen of the United States, residing in the city, county, and State of New York, 5 have invented and produced a new and original Design for Wagon-Bodies, of which the following is a specification, reference being had to the accompanying drawing, illustrating said design, in which the figure thereof o represents a perspective view.

The leading or material feature of my design is the form of projecting roof 1, whose forward end lies directly above the dashboard 2, and curved bars 3, extending from the forward end of the roof upon each side thereof and terminating in knobs or balls at points adjacent to the front ends of the sides of the

body at opposite ends of the seat. The upper forward ends of the sides 4 are cut away upon graceful curves, and in the spaces formed by the cut-away portions of the sides are located scrolls 5, the ends of which terminate in knobs or balls, the said scrolls being connected to the sides and to the bars 3.

What I claim as my invention is—
The design for a wagon-body substantially as herein shown and described.

In testimony whereof I have signed this specification in the presence of two subscribing witnesses.

CLARENCE WAINRIGHT WOOD.

Witnesses:

THOMAS P. RIDDLE,
DAVID FRIEDSAN.
